UNITED STATES PATENT OFFICE

FRANK GROSSMAN, OF BROOKLYN, NEW YORK

DESIGN FOR A SPORT SHOE OR SIMILAR ARTICLE

Application filed May 28, 1931. Serial No. 40,018. Term of patent 3½ years.

To all whom it may concern:

Be it known that I, FRANK GROSSMAN, a citizen of the United States, residing in New York city, borough of Brooklyn, in the county of Kings and State of New York, have invented a new, original, and ornamental Design for Sport Shoes or Similar Articles, of which the following is a specification, reference being had to the accompanying drawing, forming a part thereof.

The figure is a front perspective view of a sport shoe or similar article, showing my new design.

I claim:

The ornamental design for a sport shoe or similar article substantially as shown.

FRANK GROSSMAN.
